UNITED STATES PATENT OFFICE

144,893

DESIGN FOR A SHEET OF WRITING PAPER OR THE LIKE

Louis F. Bockmann, River Forest, Ill., assignor to Bockmann Engraving Company, Chicago, Ill., a firm composed of Louis F. Bockmann
and Helen R. Bockmann

Application November 23, 1945, Serial No. 124,026

Term of patent 7 years

(Cl. D59—14)

To all whom it may concern:

Be it known that I, Louis F. Bockmann, a citizen of the United States of America and residing in River Forest, Illinois, have invented a new, original, and ornamental Design for a Sheet of Writing Paper or the like, of which the following is a specification, reference being had to the accompanying drawing, forming part thereof.

The figure is a plan view of a sheet of writing paper showing my new design.

I claim:

The ornamental design for a sheet of writing paper or the like, as shown.

LOUIS F. BOCKMANN.
